UNDERFEED STOKER, INCLUDING A FUEL FEEDER PREVENTING FUEL DRAG-BACK

John S. Skelly, Monongahela, Pa., assignor, by mesne assignments, to Combustion Engineering-Superheater, Inc., a corporation of Delaware

Application November 16, 1946, Serial No. 710,260

1 Claim. (Cl. 110—47)

1

This invention relates to fuel pusher means for underfeed stokers of the type wherein an open-top retort and a reciprocating fuel pusher bar is utilized in the general manner disclosed by my U. S. Patent No. 2,049,668 of August 4, 1936, for "Fuel Burning Device."

Broadly stated, the object of my invention is to improve the design and better the performance of fuel pusher means for such stokers.

A more specific object is to raise the effectiveness and uniformity with which the stoker's reciprocating feeder bar pushes new fuel into the fuel-burning bed at the retort's open top.

Another object is to reduce the power required to reciprocate that feeder bar and the pusher parts thereto attached.

A further object is to lower the pushing surface needed to advance conveyor-delivered fuel into the main body of retort fuel and thence upwardly into the burning bed.

A still further object is to eliminate drag back of fuel on the feeder bar's return stroke and thereby raise the bar's fuel displacement efficiency from the some 60% value characteristic of prior constructions to a new value closely approaching 100%.

An additional object is to adapt the pusher parts to various types, sizes and conditions of the coal or other fuel that is to be burned by the stoker.

In practicing the invention I attain the foregoing and other objects and advantages by mounting the main pusher members on the reciprocating bar sides along the bar portion that passes through the retort end wall beneath the fuel conveyor screw; by so coordinating the member lengths with the span of reciprocating bar travel that the non-pusher member ends always stay outside the retort and hence cannot drag fuel back upon return bar travel; by utilizing in proper cases special auxiliary pushers on the bar further within the retort; and by providing means whereby the travel limits of the main pushers may be adjusted without shutting the stoker down.

An illustrative form of my invention is shown by the accompanying drawings wherein:

Figure 1 is a view in longitudinal vertical section of a stoker incorporating my inventive improvements;

Figure 2 is a section on line 2—2 of Figure 1 looking down on the top of my improved pusher parts;

Figure 3 is a section on line 3—3 of Figure 1 looking into the pusher faces of the new side

2

bar members and into the end of the fuel conveyor thereabove; and

Figure 4 is a section on Figure 2's line 4—4 through the feeder bar and one of the auxiliary pushers thereon.

Illustrative stoker to be benefited

The drawings hereof show my improvements applied to an underfeed stoker whose organization is broadly similar to that disclosed and claimed by my earlier Patent 2,049,668 above identified. This showing is merely illustrative and is not to be considered as restrictive; as the description proceeds it will become evident that my improvements also are useful with underfeed stokers of other designs.

In the stoker construction illustrated, a windbox 9 organized as in my earlier patent serves to support the stoker's open-top retort 10 within 20 the combustion chamber of a furnace. Coal or other fuel (not shown) is supplied to the retort from hopper 11 outside the furnace by way of conveyor tube 12 extending through the furnace wall 13. Fuel conveyor screw 14 within the tube 25 is rotated by motor 15 (or other power means) through reduction gearing 16, the screw speed (relatively slow as one or two R. P. M.) being selected by lever 17 to provide the desired rate of fuel supply. Entry of conveyor tube 12 into 30 the retort's end wall 18 is somewhat above the retort bottom 20 as shown.

Extending lengthwise of the retort 10 just above bottom wall 20 is the stoker's fuel feeder bar 22 which passes through front end wall 18 35 below conveyor tube 12. As here shown the bar rests on end bearing plates 23 and has the "non-packing" cross section (best indicated by Figure 4) taught by my Patent No. 2,433,713 which issued December 30, 1947, from application Serial No. 582,311, filed March 12, 1945, for "Stoker Pusher Bar."

Reciprocating motion is imparted to this feeder bar 22 by wobble cam 27 through pusher bar 25 and connecting plates 26. In the arrangement 45 shown this wobble cam is mounted in front of stoker hopper 11 outside the furnace where it is rotated with conveyor screw 14 by motor 15 at the speed (again relatively slow) selected by lever 17. Each full rotation of the cam produces a complete cycle of advance and return bar travel.

Through the medium of pusher members thereto attached (and presently to be described), the thus-reciprocated feeder bar 22 progressively advances fuel delivered into the retort by

conveyor 14 away from the retort's front end wall 18 and into the main body of retort fuel (not here shown) toward inclined rear wall 30. Such advancement displaces other fuel in that body upwardly towards the burning fuel bed at the retort's open top and outwardly upon fire bars 28-29 at the retort's top sides.

Air for supporting fuel combustion passes upwardly from windbox 9 through small passages 32 between fire bars 28-29. Such air may be maintained under pressure in the windbox by a fan (not shown) driven by motor 15 as taught by my earlier Patent 2,049,668.

All fire bars in the two side rows 28-29 may be stationary as illustrated or alternate bars 29 in each row may be arranged to reciprocate toward and from the retort 10 as disclosed by my Patent 2,142,701 of January 3, 1939, for "Underfeed Stoker." A dumping grate (not shown) also may be provided at the outer edge of each of these fire bar rows.

My improved pusher means

My invention provides improved means for causing the reciprocating movement of feeder bar 22 to push fuel in retort 10 away from the end of conveyor tube 12 and into the main body of retort fuel for the purpose of displacing other fuel in that body upwardly towards the retort's open top and into the burning fuel bed thereat as well as onto the rows of fire bars 28-29 along the retort sides.

This provision takes the form of main pusher members 36 mounted on the two sides of the pusher bar 22 (and/or on the bar top if desired, but not here so shown) along that portion of the bar which passes through the retort's end wall 18 beneath the conveyor tube 12. These members may satisfactorily take the form of metal blocks shaped as shown; they may be secured to the bar sides in any suitable manner as by means of screws 38 that pass through one of the blocks and the bar to engage with tapped holes in the opposite block as shown; and their lengths are so coordinated with the span of the bar 22's reciprocating travel that their outer or "non-pusher" ends (closest to connector plates 26) always stay outside retort 10 during the full cycle of advance and return bar travel.

In operation of the stoker the inner or "pusher" ends (which may satisfactorily be squared as shown) of these blocks 36 within the retort shove fuel thereahead during each advancing travel of the feeder bar 22 and thereby accomplish the desired function of moving fuel away from conveyor tube 12 into the main body of retort fuel. Since the outer or "non-pusher" block ends never enter the retort, the usual "drag back" of fuel upon the bar's return stroke is eliminated and maximum efficiency of fuel displacement is at once realized.

By reason of this absence of drag back I find it sometimes desirable to expose the upper end of conveyor screw 14 for direct discharge of fuel upon the top of the retort fuel bed at the bed's front end. In the arrangement shown this exposure is accomplished by a lip-like mouth 46 which inclines upwardly from the top of conveyor tube 12 to an intermediate point in the outwardly inclined fuel retainer 42 at the retort's front end.

For raising the uniformity with which the feeder bar's main pusher members 36 advance new fuel into the bed area at retort 10's open

top, I sometimes find it further desirable to utilize one or more auxiliary pusher members 44 on the feeder bar 22 closer to the center of the main body of retort fuel. In the form shown such auxiliary members have squared pusher faces, they flank the top and side edges of bar 22, and they are tapered at their opposite edges to minimize fuel drag back.

In order to adapt the improved pusher parts hereof to various types, sizes and conditions of the coal or other fuel that is to be burned by the stoker, I find it desirable in certain instances to arrange the connecting plates 26 so that the "pusher" ends of main members 36 can be set to reciprocate closer to or further away from the retort end wall 18 depending upon specific needs. In the arrangement shown such setting is made by moving the attachment of plates 26 from one location to another along the end of feeder bar 22, making use of bar pin 47 and extra plate holes 48. These parts being outside the furnace, adjustment thereof may be effected merely by stopping or declutching motor 15 and without quenching the fire in retort 10.

Advantages afforded

Underfeed stokers organized in accordance with my earlier Patent 2,049,668 of 1936 (application therefor filed in 1932) have enjoyed high commercial success in uses such as firing the boilers of heating systems for homes, apartment houses and the like as well as in other applications; this form of stoker uniquely combining the advantages of the screw feed stoker and of the sliding bottom, pusher and plunger types of stoker without being subject to the disadvantages inherent in these other stoker types.

Notwithstanding this success, prior art underfeed stokers of the type here considered have been subject to the one significant limitation that my present invention overcomes—namely, drag back of fuel to the retort front on the return feeder bar stroke. My investigations leading to the present improvement have shown that this drag back can be attributed to the prior art mounting of the first or main pushers on the retort feeder bar with the non pusher ends thereof directly contacting the fuel (as shown in Figures 1 and 9 of my Patent 2,049,668). The resultant drag back of fuel on the return feeder bar stroke directly opposes the delivery of fuel by conveyor screw 14 and has been so substantial as to make uniform distribution difficult and to result in low displacement efficiency.

These disadvantages are eliminated by my here disclosed improvement of attaching the first or main pushers 36 to the sides of the feeder bar 22 along that portion of the bar which travels through the retort wall 18 under the discharge end of the conveyor screw 14. With this improvement it requires a very much smaller pushing surface to distribute the fuel from the discharge end of conveyor tube 12, makes it very much easier to secure uniform fuel distribution through the length of the retort 10, and reduces the power required to drive the feeder bar 22.

In all prior pusher-type underfeed stokers dating from my early Patent 2,049,668 up to the present, the displacement efficiency has not exceeded about 60%; when equipped with the improved pusher means of my present invention these same underfeed stokers are found to show displacement efficiencies closely approaching 100%.

Summary

From the foregoing it will be seen that I have improved the design and bettered the performance of underfeed stokers of the type that utilize an open-top retort and a reciprocating fuel feeder bar in the general manner taught by my Patent 2,049,668; that I have raised the effectiveness and uniformity with which such a bar pushes new fuel into the fuel-burning bed at the retort's open top; that I have reduced the power required to reciprocate that feeder bar and the pusher parts thereto attached; that I have lowered the pushing surface needed to advance conveyor-delivered fuel into the main body of retort fuel and thence upwardly into the burning bed; that I have eliminated drag back of fuel on the feeder bar's return stroke and have thereby raised the bar's fuel displacement efficiency from the some 60% characteristic of prior constructions to a new value closely approaching 100%; and that I have adapted the pusher parts to various types, sizes and conditions of the coal or other fuel that is to be burned by the stoker.

My inventive improvements are therefore extensive in their application and hence are not to be restricted to the specific form here disclosed by way of illustration.

What I claim is:

Stoker mechanism comprising an open-top retort having a bottom wall extending in a substantially horizontal direction from the forward end of the retort throughout a major portion of the distance to the rear end, a fuel feed screw delivering fuel substantially horizontally into the forward end of the retort, a reciprocable fuel pusher bar extended horizontally into the retort from the region in front of the front end thereof at an elevation between the bottom wall of the retort and the feed screw, the pusher bar being located at the bottom wall of the retort and having its bottom surface substantially in contact

with the bottom wall of said retort and being of lesser width than and located intermediate the edges of said bottom wall so that fuel introduced by the feed screw rests upon the top of the pusher bar and also upon the edge portions of the bottom wall at the sides of the bar, and fuel pusher elements movable with the pusher bar and projecting laterally therefrom at the bottom wall of the retort and having their bottom surfaces substantially in contact with the bottom wall of said retort and in position to work directly horizontally against fuel at said bottom wall at the sides of the bar, the pusher elements being positioned in the region of the front end of the retort and being of sufficient length to locate the working ends thereof within the retort and the other ends thereof in front of the front end of the retort in all positions of reciprocation of said elements with the bar.
